UNITED STATES PATENT OFFICE

130,163

DESIGN FOR A PETAL CONFECTION BASKET

Effie Lue Wise, Durand, Ill.

Application May 5, 1941, Serial No. 100,775

Term of patent 3½ years

To all whom it may concern:

Be it known that I, Effie Lue Wise, a citizen of the United States, residing at Durand, in the county of Winnebago and State of Illinois, have invented a new, original, and ornamental Design for Petal Confection Baskets, of which the following is a specification, reference being had to the accompanying drawing, forming part thereof.

The figure is a perspective view of a petal confection basket, showing my new design.

I claim:

The ornamental design for a petal confection basket, as shown.

EFFIE LUE WISE.
